UNITED STATES PATENT OFFICE.

CHARLES L. CLEMENTI AND EDDIE W. HILDEBRANDT, OF PUEBLO, COLORADO, ASSIGNEES TO THE AUTO ROLLER AWNING MANUFACTURING COMPANY, OF PUEBLO, COLORADO, A CORPORATION OF COLORADO.

AWNNG.

Application filed June 25, 1926. Serial No. 118,546.

The primary intention of this invention is the provision of a protector for the windows, doors and like openings of closed vehicles which may be easily placed in position by 5 the average person by the use of a screw driver without marring the part to which the protector is attached.

The invention further supplies a protector of the awning type which when closed does 10 not obstruct the window or door opening from within or without, and in which the fabric covers the frame and hides it from view.

A further purpose of the invention is the 15 provision of an article of the nature aforesaid embodying a few number of parts, adapted to be readily folded when not required for use, and instantly extended for service and which when extended will yield 20 to prevent injury when coming in contact with an object, such as a part of the vehicle upon which the protector is installed or another vehicle or object.

While the drawings illustrate a preferred 25 embodiment of the invention it is to be understood that in adapting the means to meet specific needs and requirements, the design may be varied and such other changes in the minor details of construction may be resorted to within the scope of the invention as claimed, without departing from the 30 spirit thereof.

For a full understanding of the invention and the merits thereof, reference is to be had to the following description and the 35 drawings hereto attached, in which,—

Figure 1 is a perspective view of part 40 of the body of a closed vehicle provided with protective means for the door and window openings embodying the invention, one of the protectors being extended and the other closed.

Figure 2 is a perspective view of the 45 frame, including brackets, arms pivoted thereto, and a stretcher rod, the dotted lines illustrating the position of the fabric covering,

Figure 3 is a sectional view on the line 50 3—3 of Figure 1, looking upwardly, as designated by the arrows, showing the parts on a larger scale,

Figure 4 is a view similar to Figure 3, showing the position of the parts when the protector is folded,

Figure 5 is a sectional view on the line 55 5—5 of Figure 1,

Figure 6 is a detail sectional view on the line 6—6 of Figure 1, and

Figure 7 is a detail sectional view on the line 7—7 of Figure 1.

Corresponding and like parts are referred to in the following description and designated in the several views of the drawings by like reference characters.

While, as hereinbefore stated, the invention provides a protector of the awning type, designed chiefly for the window and door openings of a closed vehicle, nevertheless, the protector is of such construction as to be adapted for general use.

The device includes a spring roller 1, and a fabric 2, attached at one end to the roller and adapted to be automatically wound thereon by means of the usual spring forming a part of the roller. A pair of brackets 3 is provided and arms 4 are pivoted at one end thereto, the outer ends of the arms 4 being deflected and longitudinally slotted, as indicated at 5, to receive a stretcher rod 6, the ends of which are bent laterally in the same direction, as indicated at 7, to enter pockets 8 formed in the outer corners of the fabric covering 9. Each of the brackets 3 includes angularly disposed side pieces and a connecting bottom portion, to which the arms 4 are pivoted by bolts 10 to which are fitted thumb nuts, whereby the pivot fastenings may be readily adjusted to maintain a close connection between the arms 4 and the brackets. Corner portions of the bottom part of the brackets to which the arms 4 are pivoted are bent upwardly, as indicated at 11, to engage an edge portion of the arms 4 and hold the same extended against casual displacement.

The fabric covering 9 engages the stretcher rod 6 at its outer corners, as indicated at 8, and intermediate its side edges, as indicated at 12. The pockets 8 are formed by patches of the fabric stitched thereto, leaving the inner sides of the pockets open for the ingress and the egress of the bent ends 7 of the stretcher rod 6. The part 12 consists of a patch of the fabric stitched to the covering 9 along opposite edges, leaving a space for the passage of the rod 6. The bent ends 7 of the stretcher rod 6 prevent such ends from penetrating the

outer ends of the pockets. The outer deflected ends of the arms 4 and the longitudinal slots therein provide for a free movement between the arms and the stretcher rod, so that said parts may fold into a small space, as indicated most clearly in Figure 4. The outer portion of the fabric covering 9 projects a short distance beyond the stretcher rod 6, to provide a drop which hangs in front of the rod 6 and arms 4 to hide and conceal the same, as indicated most clearly to the right in Figure 1. A fringe or other part may be applied to the drop portion of the awning to give a finished effect thereto.

It is observed that the protector or awning, is adapted to be attached to the door, window or other part solely, by means of the brackets 3, and fastenings such as screws, which may be driven home by means of an ordinary screw driver. When the awning is drawn or folded, it occupies a position wholly above the opening, so as not to obstruct the view from within or without. The drop or valance of the awning fabric conceals the frame, as shown most clearly in Figure 1, to the right. The awning is extended by gripping the rod 6 and moving the same outward. This withdraws the fabric covering from the spring roller 1 and at the same time the arms 4 are extended and slide upon opposite end portions of the rod 6 and function as braces to hold the awning extended. The awning is drawn or folded, by pressing inward upon the outer ends of the arms 4 and after said arms pass points in the length of the rod 6 they automatically fold by the action of the spring roller 1 in winding the fabric 9 thereon and drawing the rod 6 into close contact with the roller. The awning fabric 9 may be readily detached from the stretcher rod 6 by disengaging the pockets 8 from the ends of the rod and drawing the latter through the slotted ends 5 of the arms and the patch 12 stitched to the covering. This admits of the awning fabric being washed or readily replaced. The construction is such that in the event of the awning striking an object when extended one or the other of the arms 4 will give, thereby preventing injury to the awning or the part struck thereby.

Having thus described the invention, we claim:

1. An awning comprising a spring roller, brackets therefor, arms pivoted at their inner ends to the brackets and having their outer ends oppositely curved and longitudi-

nally slotted, a rod passing through and supported in the outer slotted ends of the pivoted arms and an awning fabric attached to the spring roller and automatically wound thereon, and having its outer portion engaging the said rod at the ends and intermediate the ends thereof.

2. An awning comprising brackets including a bottom and side portions, the bottom portion having an edge portion deflected upwardly, a spring roller mounted in the brackets, arms pivoted at their inner ends to the bottom portions of the brackets, and having their outer ends oppositely curved and longitudinally slotted, a rod passing through and supported in the outer slotted ends of the pivoted arms, and having end portions bent laterally, and an awning covering attached to and automatically wound upon the spring roller and having its outer portion engaging the said rod at the ends and intermediate the ends thereof.

3. An awning comprising brackets, a spring roller mounted in the brackets, arms pivoted at their inner ends to the brackets, a rod supported in the outer ends of the arms which are freely slideable upon end portions thereof, said rod having its end portion bent laterally, a fabric covering attached to the spring roller and automatically wound thereon, said fabric having pockets adjacent its outer corners to receive the bent ends of the said rod and having a patch intermediate its edges to engage the middle portion of the rod, the latter detachably engaging the pivoted arms and the said fabric covering.

4. An awning comprising a pair of brackets, a spring roller pivoted to the brackets, arms pivoted at one end to the brackets and having their opposite ends curved and longitudinally slotted, a rod mounted in the slotted ends of the pivoted arms and having its ends bent laterally, and a fabric covering attached to the spring roller and automatically wound thereon and having its outer portion provided at its corners with pockets to receive the bent ends of the said rod and having a patch intermediate its edges to receive the middle portion of said rod, the top of the fabric serving to conceal the rod and pivoted arms when the awning is folded.

In testimony whereof we affix our signatures.

CHARLES L. CLEMENTI. [L.S.]
EDDIE W. HILDEBRANDT. [L.S.]
